UNITED STATES PATENT OFFICE.

FRANK A. BENFORD, OF SCHENECTADY, NEW YORK, ASSIGNOR TO GENERAL ELECTRIC COMPANY, A CORPORATION OF NEW YORK.

LIGHT-PROJECTING APPARATUS.

Application filed June 29, 1922. Serial No. 571,769.

To all whom it may concern:

Be it known that I, FRANK A. BENFORD, a citizen of the United States, residing at Schenectady, in the county of Schenectady, State of New York, have invented certain new and useful Improvements in Light-Projecting Apparatus, of which the following is a specification.

My invention relates to projector systems in which light from such sources as the high intensity arc are carried through a condenser lens to a screen or other background. Heretofore, when the light emitted by the crater of the positive electrode and by the tip of the negative electrode was thrown upon a condensing lens, this lens produced not only the image of the crater upon the screen but also an image of the negative electrode tip and of the flame of the arc above the image of the crater. In this way, two spots were obtained instead of one connected by the image of the flame. The negative spot in some instances obtrudes upon the region of the positive spot, which is also objectionable.

Among the objects of my invention are following: To provide a screen between the negative electrode, the flame of the arc and the condenser which will entirely shield the electrode while the light from the positive electrode is unobstructed and to provide detailed construction, all of which are herein-after more fully set forth and claimed.

Referring to the accompanying drawing, Fig. 1 is a view in side section in elevation, showing the shield in place; Fig. 2 is a front view in elevation of the shield; Fig. 3 is a front view in elevation of the head of the shield shown in connection with the radiating system.

Referring more in particular to the drawing, Fig. 1, the arc 2 is indicated between the positive and the negative electrodes 3 and 4 respectively of the well known type of high intensity arc. At the left is shown the condenser support frame A. Near the central portion of the support frame is shown the lens 5. Screwed to the frame of the lens is a hood 6 which may be made of any suitable material such as sheet iron, copper or the like. On the nose of the cone I have provided a heat resisting head or nozzle 7 which may be made of such material as aluminum bronze. An 8% composition may be used in which the aluminum

is 8% per cent of the total. This head must necessarily be of high refractory character on account of the intensity of the arc. I have indicated the same as being of substantial thickness. This head may be provided with radiating ribs to promote the radiation. The nozzle 7 is made, as shown, with a heavy heel, Fig. 1, just above the electrode 4. The central section of the nozzle, as indicated in Fig. 1 is formed to follow the outline of the flame of the arc 2. This flame is intensely hot and particularly so in the high intensity arc. This heat is so great that there is scarcely anything that will withstand the temperature for any length of time. It is to avoid this intense field that the nozzle is made in the particular form indicated along its central section. The upper portion of the nozzle is so constructed as to flare to the right and to the left, see Fig. 3, and at the same time taper off into a comparatively thin rim. The object of this construction is to insure a rapid dissipation of the heat imparted to the nozzle from the arc. I also contemplate using a head which is hollow, as indicated in Fig. 3, and in connection with which I propose using a radiating system through which a fluid of any suitable character may be caused to circulate; water, for example, may be used to advantage. This head 7 may be secured to the hood 6 by suitable springs 10, as indicated in Fig. 2. On the other hand, the hood itself is secured to the frame A by means of the screws 13 which are received by the slots 12 shown around the base of the cone. It will be understood that the hood 6 may be of any suitable shape, for example, it may be conical or in the shape of a pyramid. With this arrangement, the light from the positive electrode passes through the opening 11 in the nozzle and hood in the form of a tapering beam which strikes the lens 5. The apex of this beam is the positive crater and the sides are determined by the aperture 11. The hood 6 operates to cut off any light from the lens which originates outside of the crater, as, for example, from the negative electrode 4 or from the flame of the arc beyond the immediate region of the positive crater. As indicated in Fig. 3 in connection with the hollow form of head 7, I provide a radiator 8 which is connected with the head 7 by way of the conducting pipes 9 and 10. 110

The hot fluid of course rising through the pipe 9, reaches the radiator 8, where it is cooled and passes down through the pipe 10^a back into the head 7. With the use of such an arrangement, I obtain a clear cut illumination upon the screen, devoid of any of the objections above indicated.

While I have described my invention in connection with a form of apparatus shown in the drawing it will be understood that I do not limit myself to this specific form of apparatus inasmuch as variations of my invention may readily suggest themselves to those familiar with this art that do not depart from the spirit thereof or from the scope of the claims contained herein.

What I claim as new and desire to secure by Letters Patent of the United States, is:

1. In a projector, a lens, an arc lamp having a pair of electrodes the positive crater of which is located in front of the lens at a point along the optical axis of the projector whereby a tapering beam of light originating at said crater and having an axis which coincides with the said optical axis is intercepted by the lens, a hood about said beam for cutting off light from the lens originating outside of the said crater, said hood provided with an opening in juxtaposition to the crater through which opening said beam passes, and a nozzle about said opening for determining the outline of the arc flame.
2. In a projector, a lens, an arc having a pair of electrodes the positive crater of which is located in front of the lens at a point along the optical axis of the projector whereby a tapering beam of light originating at said crater and having an axis which coincides with the said optical axis is intercepted by the lens, a hood about said beam for cutting off light from the lens originating outside of the said crater, said hood provided with an opening in juxtaposition to the crater through which said

beam passes, and a nozzle about said opening for determining the outline of the arc flame, said nozzle provided with a heavy heel on one side of the arc and tapered therefrom to form a comparatively thin rim whereby the heat imparted by the arc may be rapidly dissipated.

3. In a projector, a lens, an arc having a pair of electrodes the positive crater of which is located in front of the lens at a point along the optical axis of the projector whereby a tapering beam of light originating at said crater and having an axis which coincides with the said optical axis is intercepted by the lens, a hood about said beam for cutting off light from the lens originating outside of the said crater, said hood provided with an opening in juxtaposition to the crater through which said beam passes, and a nozzle about said opening for determining the outline of the arc flame, said nozzle formed of a good heat conducting material with a cavity provided with a circulating fluid for dissipating the heat imparted to the nozzle by the arc.

4. In a projector, a lens, an arc having a pair of electrodes the positive crater of which is located in front of the lens at a point along the optical axis of the projector whereby a tapering beam of light originating at said crater and having an axis which coincides with the said optical axis is intercepted by the lens, a hood about said beam for cutting off light from the lens originating outside of the said crater, said hood provided with an opening in juxtaposition to the crater through which said beam passes, and a nozzle about said opening for determining the outline of the arc flame, said nozzle formed of aluminum bronze.

In witness whereof I have hereunto set my hand this 28th day of June, 1922.

FRANK A. BENFORD.
